UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 23,292, dated May 22, 1894.

Application filed April 13, 1894. Serial No. 507,469. Term of patent 14 years.

To all whom it may concern:

Be it known that I, EDWARD WESTON, of Newark, Essex county, New Jersey, have invented and produced a new and original 5 Design for Electrical Measuring-Instrument Cases, of which the following is a specification.

In the accompanying drawings Figure 1 is a side view of an instrument case showing my 10 design. Fig. 2 is an edge view. Fig. 3 is a section on the line 3—3 of Fig. 1, showing the conformation of the edge.

Similar letters of reference indicate like 15 parts.

The leading and characteristic feature of 20 my design is the triangular configuration of the instrument case, the said triangular figure showing two straight sides and one curved side, and there also appearing in front of said 25 curved side a bar circular in cross-section conforming longitudinally to the curve of said side.

The sides of the case, one of which is shown at A, are flat and parallel. The edge of the case, which is of much less width than the 25 sides A, shows a straight part, B, a straight part, C, at right angle to part B, and a curved part, D, extending between the parts B and C. In front of the part D appears a circular bar, E, which is of less width than the part 30 D and is supported thereon by short connecting pieces, as F. The number of connecting pieces is immaterial.

I claim—

The design for a case for electrical measuring instruments substantially as hereinbefore 35 shown and described.

EDWARD WESTON.
